DESIGN FOR A COMBINATION STATUETTE AND CONTAINER FOR PERFUME

Robert B. Karoff, New York, N. Y.

Application May 22, 1940, Serial No. 92,517

Term of patent 3½ years

To all whom it may concern:

Be it known that I, Robert B. Karoff, a citizen of the United States of America and a resident of the city, county, and State of New York, have invented a new, original, and ornamental Design for a Combination Statuette and Container for Perfume, of which the following is a specification, reference being had to the accompanying drawing, forming a part thereof,

In the drawing:

I claim:

The ornamental design for a combination statuette and container for perfume, as shown.

ROBERT B. KAROFF.
